UNITED STATES PATENT OFFICE.

BENJAMIN S. FREEMAN, OF ATTLEBOROUGH, MASSACHUSETTS.

DESIGN FOR A BRACELET-CHAIN.

SPECIFICATION forming part of Design No. 14,093, dated July 17, 1883.

Application filed January 19, 1883. Term of patent 3½ years.

To all whom it may concern:

Be it known that I, BENJAMIN S. FREEMAN, a citizen of the United States, residing at Attleborough, in the county of Bristol and State of Massachusetts, have invented and produced a new and useful Design for Bracelet-Chain, of which the following is a specification, reference being had to the accompanying drawing, forming a part thereof.

10 The figure is a plan view of my improved design for bracelet-chain.

Chain bracelets have heretofore been made with a combination of transversely-arranged parallel tubes of cylindrical form, with two or more rows of circular beads arranged at the ends of the transverse cylindrical tubes, the circular beads of one of the longitudinal rows being arranged intermediate with the circular beads of the adjoining row.

15 20 The leading feature of my invention consists in the substitution of tubes made rectangular in cross-section for the cylindrical tubes, thus presenting a flat instead of a cylindrically-ribbed surface at the sides of the chain, and also in engraving or embossing the alternate tubes of rectangular form, thus producing a highly-desirable ornamented flat surface.

In the drawing, A A' A A' are the rectangular tubes of the chain, arranged side by side adjoining each other, so that the sides of the chain may present appearance of a continuous flat surface. B B are the longitudinal rows of circular beads, placed at each end of the rectangular tubes, the beads of one row being arranged intermediate with the beads of the adjoining row. The alternate rectangular tubes A A may be made plain, and the intermediate tube, A' A', be engraved or embossed to form an ornamental contrast with the tubes A A.

I claim—

The design for bracelet-chain herein shown and described, the same consisting of the transversely-arranged rectangular tubes, presenting the appearance of a flat surface in the chain, and the longitudinal rows of circular beads, located at each end of the rectangular tubes, the beads of one row being arranged intermediate with the beads of the adjoining row.

BENJAMIN S. FREEMAN.
